L. D. KROFF

MECHANICAL TOY

Filed Nov. 9, 1925

Inventor:
Leonard D. Kroff
By Arthur F. Durand
Atty.

UNITED STATES PATENT OFFICE.

LEONARD D. KROFF, OF STERLING, ILLINOIS, ASSIGNOR TO PATENT NOVELTY COMPANY, OF FULTON, ILLINOIS, A CORPORATION OF ILLINOIS.

MECHANICAL TOY.

Application filed November 9, 1925. Serial No. 67,815.

This invention relates to mechanical toys, more particularly to those which are adapted to be pulled or propelled along the floor, and which have means operative by one or more of the wheels of the toy thereby to keep certain parts in motion, in the desired manner, while the toy is being pulled or propelled along the floor.

Generally stated, the object of the invention is to provide a novel and improved toy of the foregoing general character, having a whirling device thereon, operated by one or more of the wheels of the toy, so that when the toy is pulled or propelled along the floor, in the ordinary manner, the said whirling device will be rotated about a vertically disposed axis, thereby to provide a toy of attractive and amusing character.

To the foregoing and other useful ends, the invention consists in the matters herein-after set forth and claimed, and shown in the accompanying drawings, in which—

Fig. 1 is a plan of a toy embodying the principles of the invention.

Fig. 2 is a longitudinal section of said toy, on line 2—2 in Fig. 1.

As thus illustrated, the invention comprises a body 1 mounted on wheels 2 of suitable character. A hollow post 3 is provided substantially at the center of the toy, and a vertical shaft 4 is mounted within this post, to turn in bearings at the top and bottom thereof. The upper end of this shaft 4 is provided with a head 5, and to this head are connected the strings of beads 6 or other similar whirling means, by links 7, whereby the rotation of the head 5 will throw the beads outward, by centrifugal force, into the position shown in dotted lines.

For the rotation of the shaft 4, any suitable means can be employed. As shown, the rear axle of the wheels 2 has a pulley 8 mounted thereon, and a rubber belt 9 connects this pulley with the lower portion of the shaft 4, whereby rotation of the rear wheels will rotate the shaft 4 at the speed required to properly operate the whirling toy.

The toy is preferably propelled along the floor, by any suitable means, such as a cord 10 secured to the forward end thereof.

Thus, when the toy is pulled along the floor, the whirling device on top thereof

will be rotated to produce the desired effect, thus providing an attractive and amusing toy. As shown, the centrifugally operated and whirling elements 6 are beads strung on wires or other means, but it is obvious that any suitable means can be attached to the head 5, to be whirled around in the desired manner when the toy is pulled across the floor, without departing from the spirit of the invention.

Without disclaiming anything, and without prejudice to any novelty disclosed, what I claim as my invention is:

1. In a mechanical toy, the combination of a wheeled body, vertically disposed hollow post fixed on said body, a vertically disposed shaft associated with said post, enclosed therein, a head for the upper end of said shaft, immediately above the top of said post, and instrumentalities connected to said head to whirl therewith when the shaft is rotated, hanging normally against the sides of said hollow post, together with wheel-operated means to rotate the shaft when the toy is propelled along the floor.

2. A structure as specified in claim 1, said instrumentalities comprising beads strung on means swingingly attached to said head, so that the beads will be raised from the post and thrown outwardly by centrifugal force, when the head is rotated.

3. A structure as specified in claim 1, said post being open at its lower end for exposing the lower end of said shaft, and means for operating said shaft comprising a belt extending to wheel operated means below the body.

4. In a mechanical toy, the combination of a travelling carriage, rotatable wheels supporting said carriage, rotatable means actuated by a pair of said wheels comprising a vertical shaft extending above the carriage, a hollow supporting casing attached to the carriage and enclosing said shaft, a horizontally rotatable disk fixed to the upper end of said shaft immediately above the top of the casing, and a series of independent members pivotally attached to and depending from said disk.

5. In a mechanical toy, the combination of a traveling carriage, rotatable wheels supporting the carriage, a rotatable member above the carriage, means to rotatably sup-

port said rotatable member comprising a vertical rod and a hollow casing enclosing the rod, the said rod and casing being relatively rotatable, said rotatable member being located at the upper end of said casing, pivots on said rotatable member in substantially horizontal alignment with each other, and a series of independent members attached to

said pivots and adapted to swing outwardly in a plane coinciding with the horizontal ¹⁰ plane of the pivots when the carriage is rolled over a surface.

Specification signed this 5th day of Nov. 1925.

LEONARD D. KROFF.
